WELL DRILLING MACHINE

Howard H. Elmire, Arlington, N. J.

Application October 21, 1937, Serial No. 170,148

6 Claims. (Cl. 255—11)

The invention relates to well drilling machines.

The principal object of the present invention is to provide a well drilling machine in which the length of stroke or reciprocation on the part of the tools employed may be increased or decreased without in any way interfering with operation of the machine.

It is a well known fact that in well drilling it is often desirable to change the stroke of the tools in order to procure the most efficient results.

Such changes in stroke are advisable for various reasons, such for instance, as the changes in formation or strata through which the tools are passing or the depth of the well being drilled.

With well drilling machines in use at the present time it is necessary to shut the machine down for approximately a half an hour and oftentimes more in order to effect a change in the length of stroke and a more or less involved and laborious operation is required in making the adjustment. The

parts that have been adjusted often work loose thus causing breakage sometimes laying the machine up for considerable periods of time. It frequently happens the driller will not get the correct adjustment and the operation must be repeated. Thus considerable valuable time is lost.

In a false effort to save this time or because he does not wish to undertake the hard work of making an adjustment a driller will often keep his machine running when he knows the tools are not reciprocating with the proper stroke. This has most serious results, in that the machine is operating far from efficiently, the drilling tools may be injured or they may even break away from the cable, thus causing very expensive fishing operations.

In accordance with the present invention the length of the stroke of the tools may be varied at any time and any amount within the limits of the machine with a minimum amount of effort and without stopping the machine for an instant. Thus a great amount of time is saved and a maximum amount of efficiency is obtained by the machine.

The invention will be fully described in the following specification and illustrated in the drawings accompanying and forming part thereof. Referring to said drawings:

Fig. 1 is a side elevation with parts broken away and parts in section of a well drilling machine embodying the invention;

Fig. 2 is a fragmentary detail view taken on line 2—2 of Fig. 1;

Figs. 3 and 4 are fragmentary detail cross-

sectional views taken respectively on lines 3—3 and 4—4 of Fig. 1;

Fig. 5 is a side elevation illustrating a somewhat different embodiment of the invention;

Fig. 6 is a fragmentary detail view taken on line 6—6 of Fig. 5; and

Figs. 7 and 8 are detail cross-sectional views taken on line 7—7 and 8—8 respectively of Fig. 5.

The invention is particularly adapted to the type of well drilling machine illustrated and described in my co-pending application Serial No. 124,822, filed February 9, 1937, and reference may be had thereto. However, it is to be understood it is applicable to other known types of machine. In order to preserve simplicity and clarity in the drawings a number of parts not thought pertinent to the invention have been omitted. Among these parts are the sand reel and its associated parts, the driving connections to the cable storage drum, the brakes, and other parts.

Referring again to said drawings and particularly to Figs. 1 to 4, rigid double frame is provided which may be of any desired construction. As illustrated it comprises cross beams 5, sills 6, uprights 7 and 8 and angularly disposed reinforcing members 9, 10 and 11, all suitably secured together.

A cable-storage drum 12 is mounted on the frame between the two sides thereof and this drum carries a suitable amount of cable 13. As heretofore stated the conventional brake and driving mechanism for the drum have not been illustrated.

What is termed a stationary sheave 15 is mounted on a shaft 16 which is carried by the angularly disposed reinforcing member 9. The sheave 15 is free to rotate on the shaft 16 but is stationary as far as any actual body displacement is concerned.

The cable 13 passes from the cable-storage drum 12 over the sheave 15 and under a movable sheave 17. The movable sheave is rotatably mounted on a pin 18 carried by a pair of beams 19, hereinafter referred to as the beam 19. The beam 19 is adjustably pivoted at 20 and it is to the arrangement of this pivot that the present invention is particularly directed. The rest of the mechanism will be generally described before going into a detailed description of the adjustable pivot.

Links 26 are pivoted at one end to the pin 18 and at the other end to a pin 27 carried by another pair of beams 28 which will hereinafter be referred to as the beam 28 and this beam is pivotally mounted on a shaft 22. The cable 13

passes from under the sheave 17 to the crown pulley 29 supported by a derrick 30 and thence to the drilling tools 31, the derrick, crown pulley and drilling tools being schematically illustrated.

5 Means are provided for reciprocating the beams 19 and 28 and the sheave 17 in a vertical plane. One end of a pitman 35 is pivoted at 36 to the beam 28 and the opposite end is pivoted at 37 to a crank 38 which in turn is secured to a shaft 39. The shaft 39 has a gear 41 secured thereto and this gear meshes a pinion 42 which is on the shaft 43, a pulley 44 is secured to the outer end of the shaft 43 and a belt 45 passes over this pulley and another one 46 on a shaft 47 which is driven by a suitable motor or engine indicated at 48.

It will be apparent that as the beams 19 and 28 reciprocate the sheave 17 the tools 31 will be raised and dropped through the medium of the cable 13. As heretofore stated it is important to have absolute control of the amount of reciprocation of the tools. By moving the pivot 20 of the beam 19 toward or away from the pivot 22 the stroke of the sheave 17 will be decreased or increased and it follows the amount of reciprocation of the tools will consequently be effected in a similar manner. In accordance with the invention means are provided for moving this pivot without, even momentarily, interfering with the operation of the drilling machine. While two means for doing this are illustrated and described it is to be understood numerous other methods might be devised and they are to be construed as being the equivalent of that illustrated.

30 The shaft 20 is carried in a block 50 and this block is slidably mounted in a channel-shaped guide 51. One end of this channel guide is carried on the shaft 22 and the opposite end is supported by and attached to a bracket 52 which in turn is carried by the uprights 8. The channel-shaped guide is slotted as indicated at 53 and the arrangement is such that the block 50 may slide in the guide but cannot be moved out of engagement with the guide.

35 The block 50 has secured thereto or made integral therewith a threaded stem 54. The threaded stem 54 is engaged by a nut 55 which is free to rotate but is fixed against longitudinal movement by a set screw 56.

40 The nut 55 may be secured to or made integral with a sprocket 57 and a sprocket chain 58 connects this sprocket with another sprocket 59 carried by a shaft 60. A hand wheel 61 is secured to the shaft 60 at any appropriate location and

45 from the foregoing it is thought to be apparent that manipulation of this hand wheel will raise or lower the pivot shaft 20 and thus decrease or increase the reciprocation or stroke of the tools without interfering with the operation of the

50 machine. It will also be noted that very fine adjustments may be obtained with the greatest of facility and dispatch. While as heretofore stated this mechanism is particularly adapted to this type of machine it is to be understood it may be applied to other known machines.

55 Referring to Figs. 5 to 8 similar reference characters denote similar parts and only those parts of the machine necessary to an understanding of the invention have been illustrated. In Figs. 1 to 4 the pivot adjusting means might be said to be located generally in the center of the machine while at Figs. 5 to 8 the pivot adjusting means is located on the sides of the machine. This 60 makes for greater accessibility both as to instal-

lation and for making any repairs or adjustments that might be necessary at future times.

65 The pivot adjusting means is advantageously positioned on the angularly disposed reinforcing members 9. However this is just a matter of expediency and not necessity as in a machine where these members are non-existent other supporting means would be provided to carry the pivot adjusting means. As both sides of the machine are duplicates with the exception of the 70 control means a description of one will suffice for both.

75 Guides 70 are suitably secured to the reinforcing members 9 and slidable blocks 71 are mounted in these guides. The pivot shaft 20 is extended 80 on both sides and is carried by the blocks 71. As in the form of the invention heretofore described the blocks 71 have threaded extensions 72 made integral therewith or suitably secured thereto.

85 A stationary block 73 forms the lower end of the guide and a nut 74 which is free to rotate but held against longitudinal movement is mounted in the block 73. This nut engages the threaded stem 72 and is secured to or formed 90 integral with a sprocket 75. A sprocket chain 76 connects the sprockets 75 so as to insure both sprockets moving simultaneously and in synchronization with each other.

95 One of the sprockets 75 has an additional sprocket 77 secured thereto or made a part thereof and a sprocket chain 78 connects the sprocket 77 with another sprocket 79 secured to shaft 10 mounted in suitable bearings on either side of the frame. A hand wheel 81 is secured to 100 the outer end of the shaft 80 for manipulation thereof.

From the foregoing it is thought to be apparent that as the hand wheel 81 is turned in one direction or the other the beam pivot 20 will be moved toward or away from the pivot 22 and the stroke of the tools will be decreased or increased. It is again desired to call attention to the fact of being able to control the amount of reciprocation or stroke of the tools with the most minute degree of accuracy. The common method of changing the stroke of the tools is by moving a crank pin from one hole to another. It often happens the most desirable stroke of the tools will be obtained at some intermediate position it is impossible to attain. Thus, by having absolute control of the amount of stroke of the tools, the most efficient results are obtained with great saving of time and energy.

Such changes in details of construction and arrangements of parts as would occur to one skilled in the art are to be considered as coming within the spirit of the invention as set forth in the appended claims.

105 I claim:

1. A well drilling machine having in combination, a frame, a cable-storage drum, a stationary sheave, a pair of beams pivotally mounted in said frame, a sheave carried by said beams, a cable passing from said storage drum over said stationary sheave and under the sheave carried by said beams, means whereby said sheave is reciprocated in a vertical plane, and means in permanent operative relation with the pivot of one of said beams whereby the said pivot may be moved in relation to the pivot of the other of said beams to vary the stroke thereof; said means being operable while said machine is functioning.

2. A well drilling machine having in combination, a frame, a cable-storage drum, a stationary

sheave, a pair of beams pivotally mounted in said frame, a sheave carried by said beams, a derrick, a crown pulley carried by said derrick, a cable passing from said storage-drum over said stationary sheave, under said sheave carried by said beams and over said crown pulley, drilling tools carried by said cable, means whereby said movable sheave is reciprocated in a vertical plane, and means in permanent operative relation with the pivot of one of said beams whereby said pivot may be moved in relation to the pivot of the other of said beams to vary the stroke of the drilling tools carried by said cable, said means being operable while said machine is functioning.

15. 3. A well drilling machine having in combination, a frame, a cable-storage drum, a stationary sheave, a beam pivoted in said frame, a sheave carried by said beam, a cable passing from said storage-drum over said stationary sheave and under the sheave carried by said beam, blocks in which the pivot of said beam is mounted, guides for said blocks, and means whereby said blocks may be synchronously moved in said guides so as to vary the stroke of said beam, said means being operable while said machine is functioning.

20. 4. A well drilling machine having in combination, a frame, a cable-storage drum, a stationary sheave, a pair of beams pivotally mounted in said frame, a sheave carried by said beams, a cable passing from said storage-drum over said stationary sheave and under the sheave carried by said beams, means whereby said sheave is reciprocated in a vertical plane, guiding means for the pivot of one of said beams, and means whereby the pivot may be moved in said guiding means so as to vary the stroke of said beam, said means being operable while said machine is functioning.

25. 5. A well drilling machine having in combina-

tion, a frame, a cable-storage drum, a stationary sheave, a pair of beams pivotally mounted in said frame, a sheave carried by said beams, a derrick, a crown pulley carried by said derrick, a cable passing from said storage-drum over said stationary sheave, under said sheave carried by said beams and over said crown pulley, drilling tools carried by said cable, means whereby said movable sheave is reciprocated in a vertical plane, blocks in which the pivot of one of said beams is mounted, guides on said frame for said blocks, and means whereby said blocks may be synchronously moved in said guides so as to vary the stroke of the drilling tools carried by said cable, said means being operable while said machine is 10

15

6. A well drilling machine having in combination, a frame, a cable-storage drum, a stationary sheave, a pair of beams pivotally mounted in said frame, a sheave carried by said beams, a derrick, a crown pulley carried by said derrick, a cable passing from said storage-drum over said stationary sheave, under said sheave carried by said beams and over said crown pulley, drilling tools carried by said cable, means whereby said movable sheave is reciprocated in a vertical plane, blocks in which the pivot of one of said beams is mounted, guides on said frame for said blocks, 20

25

threaded stems secured to or forming a part of said blocks, nuts engaging said threaded stems, 30

35

said nuts being free to rotate but fixed against longitudinal movement, and means whereby said nuts may be synchronously rotated to move said blocks in said guides so as to vary the stroke of the drilling tools carried by said cable, said means being operable while said machine is functioning.

HOWARD H. ELMIRE.
